UNITED STATES PATENT OFFICE.

ARTHUR ALLISON AND JOHN WALTER KEY, OF TAFT, CALIFORNIA.

PIPE-WRENCH.

1,175,399.

Specification of Letters Patent. Patented Mar. 14, 1916.

Application filed April 12, 1915. Serial No. 20,729.

To all whom it may concern:

Be it known that we, ARTHUR ALLISON and JOHN WALTER KEY, citizens of the United States, residing at Taft, in the 5 county of Kern, State of California, have invented new and useful Improvements in Pipe-Wrenches, of which the following is a specification.

This invention relates to pipe wrenches, 10 and particularly to wrenches adapted for handling heavy and large pipe; and it is a primary object, among others, to provide a wrench with which the pipe may be strongly engaged without danger of crushing or dis- 15 torting the pipe.

We accomplish our objects primarily by the provision of a flexible pipe engaging jaw which will adjust itself to different sizes of pipe and which will lie in close and 20 intimate contact with the surface of the pipe, affording good engagement therewith over a comparatively large area; so that, although great traction on the pipe is secured, the pressure required to secure this 25 traction is spread over a large area on the pipe and crushing or distortion is thereby obviated.

The particular features of our invention, and the advantages and utilities thereof, are 30 best explained in the following specification, reference being had to the accompanying drawings, in which, for the purpose of this specification, we illustrate a preferred and specific form of our invention, and in 35 which drawings—

Figure 1 is a sectional view showing our wrench applied to a pipe, Fig. 2 is a view taken as indicated by line 2—2 on Fig. 1, and Fig. 3 is an enlarged detail taken from 40 Fig. 1.

In the drawings the numeral 10 designates a pipe about which our wrench may be engaged; the pipe shown in the drawings being one of relative medium size. It will 45 be understood that our wrench will engage the pipe of greatly varying sizes. We provide a suitable lever handle 11 of any desired length; and to this handle we pivot preferably a pair of jaw supporting mem- 50 bers 12, said members being preferably pivoted at the same point 13 as shown in the drawings. As herein stated, it is of the essence of our invention to provide a flexible pipe engaging jaw, and it is necessary to 55 provide some sort of movable support for the ends or other parts of this flexible en-

gaging jaw. We prefer to provide these movable or adjustable jaw supporting members in the form of the pivoted members 12, as shown. At the outer free ends of the 60 members 12 we provide the pipe engaging members 14, which preferably have keys 15 set therein, said keys being square or diamond shaped in cross section and engaging the pipe 10 with one of their sharp edges. 65 Between the two members 14 we connect our pipe engaging jaw 16, which is flexible and preferably comprises a flexible chain connected at opposite ends with the members 14. We prefer to use a flexible chain 70 for this purpose, although other constructions may be used instead. A spring mechanism 17 serves to normally press the pivoted members 12 apart; so that when pressure is relieved, the members will be forced 75 apart and the jaw chain 16 will be pulled toward a straight line position. This provision is both for the purpose of raising the pipe engaging members 14 from the pipe 80 upon each backward stroke of the wrench and also for throwing the members 14 apart so that the wrench may be easily applied to a pipe without the necessity of manually separating the two members 14.

The spring mechanism 17 is shown in 85 detail in Fig. 3. It will be noted that each of the members 12 is double, each comprising two bars 12^a one on each side of the lever handle 12. Rods 20 extend transversely between the two opposite bars 12^a of each 90 pivoted member 12; and the spring mechanism 17 is confined between these two transverse rods 20. A spring 21 is confined between heads 22 and 23, head 22 resting against a nut 24 screw threaded upon a 95 sleeve 25, and head 23 being mounted upon a sleeve 26, sleeve 25 preferably working in the sleeve 26. Pins 27 are mounted upon the cross bars 20 and enter the two sleeves 25 and 26. The spring 21 is set in proper tension by adjustment of the nut 24; and expansion of the spring tends to throw the cross rods 20 away from each other and to throw the pivoted members 12 away from each other about their common center 13. 105

We employ means for holding the wrench upon a pipe of any size, said means holding the flexible jaw against the pipe. As a specific form of said means we prefer to utilize a flexible member such as a chain 110 30 attached at one end as at 30^a to one of the members 14. Provision is made for securing

the other end of the chain to the end of lever handle 11. We prefer to provide a removable and renewable plate 31 having teeth or projections 32 upon which the chain links may be engaged; the plate being removably held on the handle 11 by screws 33 or other suitable means. Thus, when the plate 31 becomes worn or broken it is not necessary to renew the whole handle.

10. It will be seen that our wrench may be applied to pipes of greatly varying sizes; and that the flexible pipe engaging jaw conforms exactly to the curvature of any pipe, being pressed closely and intimately into 15 engagement with the pipe so that a large bearing surface is formed. Great pressure may be exerted upon the pipe in order to obtain a correspondingly great purchase thereon without any liability of crushing 20 or deforming the pipe.

Having described a preferred form of our invention, we claim:

1. A pipe wrench, embodying a lever handle, a plurality of jaw supporting members 25 movably mounted upon the handle, a flexible pipe engaging jaw attached between the movable members, and means to hold the jaw against a pipe.

2. A pipe wrench, embodying a lever 30 handle, a plurality of jaw supporting members pivoted each at one end to the handle, a flexible pipe engaging jaw attached at opposite ends to the free ends of the pivoted members, and means to hold said jaw 35 against a pipe.

3. A pipe wrench, embodying a lever handle, a pair of jaw supporting members each pivoted at one end to the handle, a flexible pipe engaging jaw comprising 40 a chain attached at opposite ends to the free ends of the pivoted members, and means for holding the flexible jaw against the pipe embodying a chain attached at one end to one of the pivoted members, and means for 45 securing the other end of the chain to the handle.

4. A pipe wrench, embodying a lever 50 handle, a pair of jaw supporting members pivotally attached at a common pivotal point to said handle, a flexible pipe engaging jaw comprising a chain attached at opposite ends to the free ends of the pivoted members, and means for holding the flexible jaw against the pipe embodying a chain 55 attached at one end to one of the pivoted members, and means for securing the other end of the chain to the handle.

5. A pipe wrench, embodying a lever

handle, a pair of jaw supporting members pivotally attached at a common pivotal 60 point to the lever handle, pipe engaging members pivotally attached one to the free end of each of said pivoted jaw supporting members, a flexible pipe engaging chain connected between the two pipe engaging 65 members, and means for holding the pipe engaging chain and the pipe engaging members against a pipe.

6. A pipe wrench, embodying a lever 70 handle, a pair of jaw supporting members pivotally attached at a common pivotal point to the lever handle, pipe engaging members pivotally attached one to the free end of each of said pivoted jaw supporting members, a flexible pipe engaging chain 75 connected between the two pipe engaging members, and means for holding the pipe engaging chain and the pipe engaging members against a pipe, said means embodying a flexible chain attached at one end to one 80 of said pipe engaging members and means for securing the other end of the chain to the lever handle.

7. A pipe wrench, embodying a lever 85 handle, a plurality of jaw supporting members pivoted each at one end to the handle, and spring means tending to throw the two pivoted jaw supporting members apart from each other, a flexible pipe engaging jaw attached at opposite ends to the free ends of 90 the pivoted members, and means to hold said jaw against a pipe.

8. A pipe wrench, embodying a lever 95 handle, a plurality of jaw supporting members pivoted each at one end to the handle, and spring means tending to throw the two pivoted jaw supporting members apart from each other, pipe engaging members pivotally attached one to the free end of each 100 of said pivoted jaw supporting members, a flexible pipe engaging chain connected between the two pipe engaging members, and means for holding the pipe engaging chain and the pipe engaging members against a pipe, said means embodying a flexible chain 105 attached at one end to one of said pipe engaging members and means for securing the other end of the chain to the lever handle.

In witness that we claim the foregoing we have hereunto subscribed our names this 110 31st day of March 1915.

ARTHUR ALLISON.
JOHN WALTER KEY.
